UNITED STATES PATENT OFFICE.

JAMES R. CARDWELL, OF CHICAGO, ILLINOIS, ASSIGNOR TO UNION DRAFT GEAR CO.,
A CORPORATION OF ILLINOIS.

DRAFT GEAR.

Application filed November 21, 1924. Serial No. 751,216.

To all whom it may concern:

Be it known that I, JAMES R. CARDWELL, a citizen of the United States, and resident of Chicago, county of Cook, and State of Illinois, have invented certain new and useful Improvements in Draft Gears, of which the following is a specification, and which are illustrated in the accompanying drawings, forming a part thereof.

10 This invention relates to draft gears for railway trains and more particularly to the friction type of draft gear.

One of the objects of the invention is the provision of a new and improved gear in which the forces of compression will be more nearly distributed according to the strength of the material than has heretofore been possible with the constructions in general use.

20 Another object of the invention is the provision of a new and improved arrangement of chambered followers and solid follower blocks.

Other and further objects and advantages 25 of the invention will appear from the following description taken in connection with the accompanying drawings, in which

30 Fig. 1 is a horizontal section of the center sills of a railway car showing my invention in position thereon, with parts broken away, the parts being shown in the relation they occupy under the buff;

Fig. 2 is a vertical section along line 2—2 of Fig. 1, with parts broken away; and

35 Fig. 3 is a side view of the wedge block.

In the type of gear in which the wedge block is provided with a transverse opening therethrough it has been found by experiment that the compression force if 40 transmitted through all portions of the block equally will tend to split the block longitudinally in the plane of the hole. The present invention is adapted to overcome this difficulty.

45 On the drawing the reference character 10 designates the center sills of a railway car. Each sill is provided with a buffer lug 11 and a draft lug 12.

The draft gear mechanism comprises two 50 opposed chambered followers or gear casings 13. Follower bars 15 and 16 are inserted between the chambered followers 13 and the shoulders, respectively. The coupler

butt 17 is provided with a yoke 18 which embraces the gear casings 13 and the bars 55 15 and 16.

Friction means are associated with the casings to resist their compression. As shown, this means comprises a wedge block 19 having the inclined faces 21 at each end 60 thereof which converge outwardly. The wedge block 19 is provided with tongues 20 on its upper and lower faces for engaging corresponding grooves 200 in the casings, for positioning the block. It is also provided with an elongated opening 22 extending transversely through its central portion. A tension rod or bolt 23 is adapted to extend through said block, the sides of said casing and through the sills 10. A shoe 24 is slidably mounted on said rod at each side of said block within said casing. Springs 25 mounted on the outer ends of said rod are adapted to engage sleeves 26 interposed between said springs and shoes for 75 resisting the outward movement of said shoes due to the draft and buffing stresses, as will presently appear.

The shoes 24 are provided on their inner surfaces at each end thereof with inclined 80 friction faces 27 which are adapted to be engaged by wedges 28. The wedges 28 are adapted to be forced between the shoes and the wedge block 19 by the draft and buffing action of the yoke 18. The friction between the wedges 28 and the inclined surfaces of the shoes and wedge block and between the wedges and the followers induced by the resistance of the springs 25 is adapted to absorb the normal buffing stresses to 90 which the draft gear is subjected in actual use.

The walls of the casings 13 and 14 are not of sufficient strength to resist the compression to which the gear is sometimes subjected, consequently the wedge block is of such length that it will reinforce the central portions of the casings 13 and 14 and will, as a matter of fact, constitute the principal abutment for the followers 15 and 16 when 100 the gear is entirely collapsed by abnormal buffing stresses.

In order that little or none of the buffing stresses shall be transmitted through the wedge block 19 along a line intercepting the 105 opening 22 of said block when the gear is

entirely collapsed, provision is made whereby that portion of the wedge block opposite said opening will not come in contact with the bottoms of said casings 13. This 5 may be accomplished by providing a recess in either the followers or in the ends of the blocks, or in both, said recesses or notches being arranged in the plane of the opening 22.

10 In the form of the device selected to illustrate one embodiment of the invention each end of the wedge block 19 is provided with a recess or groove 29 extending entirely across the block parallel with the axis of 15 said opening. The casings 13 may also be provided with corresponding recesses 31 arranged opposite to said recesses 29, respectively.

By means of this arrangement, the buffing 20 stresses which are sufficiently severe to cause the gear to collapse will be transmitted through the upper and lower solid portions of the wedge block 19, the central apertured portion of the block not being affected except 25 indirectly, consequently there will be no tendency to separate the block along its median line.

The casings 13 are preferably of softer material than the wedges in order to provide 30 an efficient friction surface for the bases of the wedges 28 which are of relatively hard material. Preferably malleable iron is employed for the casings. The continued hammering of the yoke 18 against the central 35 portion of the casings tends to distort the bottoms of the same, and where the casings are of malleable iron the frictional surfaces of the bottoms of the casings which engage the wedges are likely to become distorted, 40 thereby affecting the surface contact of the sides of the wedges with the inclined surfaces of the shoes and wedge block. In order to overcome this difficulty and at the same time form the casings of different material 45 from the wedges, a pair of steel followers 15 and 16 are employed. These followers will not become permanently distorted by the buffing action but will distribute the stress equally to both sets of 50 wedges.

It is thought from the foregoing taken in connection with the accompanying drawings that the construction and operation of my device will be apparent to those skilled 55 in the art, and that various changes in size, shape, proportion and details of construction may be made without departing from

the spirit and scope of the appended claims.

I claim as my invention:

1. In a compressible draft gear of the 60 friction type, a pair of followers, means for yieldingly resisting the compression of said gear, said means comprising a wedge block between said followers and adapted to engage the same during severe buffing stresses, 65 said wedge block being provided with a solid and an apertured portion, and means whereby the severe buffing stresses will all be transmitted through the solid portion of said block.

2. In combination, a pair of chambered followers, a wedge block within said followers and adapted to be engaged thereby during the collapsing of said followers, said block being provided with an opening and 70 with a recess at each end thereof opposite said followers and in the plane of the longitudinal axis of said opening, means including a member extending through said opening for frictionally resisting the collapsing 75 of said followers and for returning the parts to normal position after compression.

3. In a draft gear, a pair of follower members, a friction block between said members, and means including a rod extending 80 through a transverse opening in said block for yieldingly resisting the compression of said members, said block and members being provided with oppositely arranged recesses in the plane of said opening.

4. In a draft gear, a pair of follower members, a friction block between said members, and means including a rod extending 90 through a transverse opening in said block for yieldingly resisting the compression of members, said members being provided with recesses opposite the ends of said block in the plane of said opening and each of a size equal to a cross section of said opening 95 whereby the buffing stresses will be transmitted through the solid portions of said block at each side of said opening when the follower members engage the ends of the block as the gear goes solid.

5. In a draft gear for railway cars, a 105 wedge block comprising a metallic bar having its ends provided with inclined faces converging outwardly, said block having an opening extending transversely through its central portion and each end thereof provided with a depression in the longitudinal axis thereof.

In testimony whereof I affix my signature.
JAMES R. CARDWELL.
